[57] CLAIM

The ornamental design of a tire, as shown and de-
scribed.

DESCRIPTION

FIG. 1 is a perspective view of a tire showing our new
design, it being understood that the tread pattern is
repeated throughout the circumference of the tire, as
shown schematically by solid lines, the opposite side
being the same as the side shown;

FIG. 2 is an enlarged fragmentary side elevational view
thereof; and

FIG. 3 is an enlarged fragmentary plan view thereof.
